UNITED STATES PATENT OFFICE.

EDWARD B. HESS, OF MANHATTAN BEACH, NEW YORK, ASSIGNEE TO ROYAL TYPE-WRITER COMPANY, INC., OF NEW YORK, N. Y., A CORPORATION OF NEW YORK.

TYPEWRITING MACHINE.

Application filed September 12, 1921. Serial No. 500,184.

To all whom it may concern:

Be it known that I, EDWARD B. HESS, a citizen of the United States, residing at Manhattan Beach, Kings County, New York, N. Y., have invented certain new and useful Improvements in Typewriting Machines, of which the following is a specification.

This invention relates particularly to type actions for typewriting machines and especially to type actions of the kind employed in front strike visible machines in which the type bars are moved from a position of rest toward the platen by the keys which are connected to the type bars by interposed actuating devices. In some such machines the actuating devices are arranged in advance of the type bar pivots. In other machines the actuating mechanism is located in rear of the pivots of the type bars. My present invention relates to the latter class of machines and according to my invention connections are made between the key levers and the type bars by means of intermediate levers, which are arranged in rear of the type bar pivots and are so connected to the heels of the type bars as to exert a rearward pull thereon. Preferably, bell-crank levers are employed, the shorter arms of which are operatively related with the key levers, while the longer arms, which are arranged in rear of the type bars, are connected to the heels of the type bars by links arranged in a novel way. The escapement mechanism is actuated by the bell-crank levers, which operate a universal bar equipped with improved cushioning and return devices.

Unless there is some means provided to prevent it, considerable noise is produced in the operation of the machine by the impact of the type on the platen. In my application for patent filed July 1, 1921, now Patent No. 1,390,708, dated Sept. 13, 1921, I have shown, described and claimed means for reducing this noise by so connecting the key levers with the type bars that the type bars are moved positively to a position in front of the platen and at a considerable distance therefrom, the further movement of the type bars to the platen being caused by the momentum thereof. In the machine shown in said application for patent, the connections between the key levers and the type bars are made to the lower portions of

the heels of the type bars. According to my present invention, the links which connect the heels of the type bars to their operating levers are arranged in rear of the pivots of the type bars, the connections of the links being made to said heels above their pivots, and in the operation of the machine the upper ends of the heels of the type bars are pulled rearwardly to move the type bars positively toward the platen.

The two-arm or bell-crank levers which are interposed between the key levers and the type bars are operatively related to a universal bar, arranged in rear of them, the arrangement being such that when the type bars are actuated the bell-crank levers, through their link connections with the type bars, move the type bars in the manner before described and also operate the universal bar. Said universal bar comprises a frame carrying a pad, with which the bell-crank levers make contact, said frame being provided with an arm which makes contact with the escapement mechanism. The pad-carrying frame is secured to a plate, which is mounted on swinging links, and the movement of the frame is cushioned by a spring or buffer, which operates to return the universal bar to normal position.

In the accompanying drawings, Figure 1 is a view, largely diagrammatic, of portions of a typewriting machine embodying my improvements, some parts being shown in side elevation and some in section;

Figure 2 is a detail view illustrating the link-connection between the heel of a type bar and the upper end of a bell-crank lever, the parts being indicated in a dead-center position when the pivot points at opposite ends of the link are in a straight line with the pivot of the type bar;

Figure 3 is a view, similar to Fig. 2, but showing the parts in a different position—that is, when the pivot points at opposite ends of the link have passed the dead-center position.

In Figure 1 parts of a typewriter carriage are indicated at A, and B indicates a platen. C indicates a type bar segment, D a type bar guide and E parts of a ribbon vibrator. Escapement mechanism is indicated at F, a key lever at G, and a type bar at H. The type bars normally lie horizontally, their inner ends being pivoted to

the segment at h , and their front ends being supported by a cushioned rest I. The key levers are pivoted at g near their rear ends, and operate in a comb guide J. The 5 upward or return movement of the keys is limited by a cushioned stop K. The heel h' of each type bar is connected by a link L with the upper end of a bell-crank or two-arm lever M, pivotally mounted at m below 10 the key levers and having a rearwardly extending arm m' provided with an anti-friction roller m^2 , bearing against a key lever. It will be understood that each of the type 15 bars is connected with a bell-crank lever of the kind shown, and each bell-crank lever is operatively related to a key lever as indicated.

The heel of each type bar is connected with an associated key by a coiled spring N, 20 which serves to hold the type bar and the key lever with which it is connected in normal positions and to assist in returning them to these positions after being operated.

Each of the levers M is adapted to operate 25 the universal bar mechanism indicated generally at O. This mechanism comprises a semi-circular frame o, carrying a cushion o', and supported by a plate o², having upwardly extending lugs o³, to which are pivotally connected the upper ends of links P, the lower ends of which are pivotally connected at p to a stationary part Q of the machine frame. The frame Q is formed with a member q, having an opening in it 35 through which extends a bolt R, pivoted to one of the front links P at p' and carrying a coiled spring R', which is interposed between the front link P and the member q. At its rear end, in rear of the member q the 40 bolt carries adjusting nuts r, by means of which the tension of the spring may be varied. The arrangement is such that normally the parts o, o' of the mechanism are held against the levers M and when the upper ends of these levers are moved rearwards 45 the universal bar is correspondingly moved against the force of the spring R'. The frame o is provided with a rearwardly extending arm S, which is adapted to make 50 contact with a roller f' on the arm f, forming part of the escapement mechanism. As this escapement mechanism is of the well-known Royal type, it need not be further described. It will be observed, however, 55 that when the key levers and type bars are in normal position the arm S is arranged a considerable distance from the roller f', so that in the operation of the machine the escapement mechanism is not actuated until 60 after the levers M have moved to a considerable extent—that it, until the type bars have reached the position shown by the dotted lines Z, in Fig. 1.

As before stated, the levers M are located 65 in rear of the type bar pivots, while the

links L are connected to the heels of the type bars above these pivots. The point of connection of a link L with the heel of a type bar at x moves rearwardly and downwardly when its associated key is depressed, while the point of connection y , between the lever M and the link, also moves rearwardly.

When a key is operated the associated lever M is so moved as to pull the type bar toward the platen and said lever also engages the universal bar and operates the escapement mechanism in the manner before described. The connections between the links L and the levers M and the type bars H are so made that when a key is depressed the associated type bar is first moved to the position shown by the dotted lines at Z, in Fig. 1. This operation is performed by a full depression of a key. At that time the pivot points h , x and y are arranged in a straight line with each other, i. e., they are in a dead-center position, as indicated in Fig. 2. No further depression of the key, therefore, occurs, but the momentum of the type bar carries it to the printing point, as indicated at Z', and the pivot points h , x , y , assume the positions shown in Fig. 3. In this way noise caused by the impact of the type on the platen is greatly reduced.

It will be observed, by reference to Fig. 1, that when a type bar reaches the position Z, the link L occupies the dead-center position shown at 1, and when the type bar moves forward to the platen the link L occupies the position shown by the dotted line 2, the dead-center position then being broken. It will be understood that when this dead-center position is broken the key lever makes a short return movement, which is resisted by the finger of the operator, and this also assists in decreasing the speed of the type bar and thus reducing noise. By a full depression of a key the associated type bar is moved to a position which is considerably more than five degrees from the printing point. The drawings show approximately such position, but this position may be somewhat varied.

In general, the arrangement of the mechanism is such that the type bars are moved to the platen in such manner as to greatly reduce noise and the escapement mechanism is actuated while the type bars are being carried by their momentum at reduced speed near the end of their movement to the printing point, these features of the invention being embodied in a machine where the type bars are actuated by mechanism located in rear of their pivots.

I claim as my invention:

1. In a typewriting machine, the combination with the key levers and type bars of levers in rear of the type bars which have arms operatively related with the key levers, and arms having their upper ends link-con-

nected to the heels of the type bars above their pivots, the points of connection of each link with its type bar and associated lever arm being so related that a full depression of the key lever moves them into a straight line with the type bar pivot, the type bar then being at a considerable distance from the platen and completing its movement by its own momentum.

- 10 2. In a typewriting machine, the combination with the key levers and type bars of bell-crank levers in rear of the type bars which have arms operatively related with the key levers, and arms having their upper ends link-connected to the heels of the type bars above their pivots, the points of connection of each link with its type bar and associated lever arm being so related that a full depression of the key lever moves them into a straight line with the type bar pivot, the type bar then being at a considerable distance from the platen and completing its movement by its own momentum.

- 15 3. In a typewriting machine, the combination with horizontally arranged key levers and horizontally arranged type bars, of bell crank levers in rear of the type bars which have short arms operatively related to the key levers and long arms having their upper ends link-connected with the heels of the type bars above their pivots, the points of connection of each link with its type bar and associated lever arm being so related that a full depression of the key lever moves them into a straight line with the type bar pivot, the type bar then being at a considerable distance from the platen and completing its movement by its own momentum.

- 20 4. In a typewriting machine, the combination of a type action comprising a sub-lever, a universal bar in the rear thereof to be actuated thereby, means for supporting said universal bar to permit it to move fore and aft and comprising an arm, a bolt con-

nected to said arm and having limited movable engagement with a fixed lug, and a spring surrounding said bolt, whereby the return movement of the universal bar is produced and limited.

25 5. In a typewriting machine, the combination with the key levers and type bars of levers in rear of the type bars which have arms operatively related with the key levers, and arms having their upper ends link-connected to the heels of the type bars above their pivots, the points of connection of each link with its type bar and associated lever arm being so related that a full depression of the key lever moves them into a straight line with the type bar pivot, the type bar then being at a considerable distance from the platen and completing its movement by its own momentum, and a universal bar in the rear of the type bar pivots and operative only through the momentum period of the type bar.

30 6. In a typewriting machine, the combination with the key levers and type bars of levers in rear of the type bars which have arms operatively related with the key levers, and arms having their upper ends link-connected to the heels of the type bars above their pivots, the points of connection of each link with its type bar and associated lever arm being so related that a full depression of the key lever moves them into a straight line with the type bar pivot, the type bar then being at a considerable distance from the platen and completing its movement by its own momentum, and a universal bar in the rear of the type bar pivots and in the rear of the sub-levers, and operated directly by the sub-levers only during the momentum period of the type bar.

35 In testimony whereof, I have hereunto subscribed my name.

EDWARD B. HESS.
